MOTOR VEHICLE PROVIDED WITH FOUR
INDEPENDENT WHEELS

René Jean Devillers, Paris, France, assignor, by
mesne assignments, to Daimler-Benz Aktien-
gesellschaft, Stuttgart-Untertürkheim, Ger-
many, a corporation of Germany

Original No. 1,915,649, dated June 27, 1933, Serial
No. 335,084, January 25, 1929. Application for
reissue June 22, 1935, Serial No. 27,875. In
France January 27, 1928

12 Claims. (Cl. 280—112)

This invention relates to motor vehicles with independently spring-supported wheels and the object is to provide a construction of such vehicle which will be easy steering and easy riding and at the same time steady and stable.

5 My invention may be understood by reference to the following description taken in connection with the accompanying drawing illustrating in a diagrammatic manner a single embodiment 10 thereof and in which:

Fig. 1 is a front end elevation of a motor vehicle embodying the invention;

Fig. 2 is a similar view showing the vehicle when driving around a corner;

15 Fig. 3 is a side elevation;

Fig. 4 is a rear elevation of such a motor vehicle;

Fig. 5 the rear end elevation of the motor vehicle when driving around a corner;

20 Fig. 6 is the rear end elevation of the motor vehicle, as appearing when one wheel is passing over an obstacle.

In the customary mounting of automobile bodies with the two front or steering wheels on a single axle or transverse member from which the body is spring-supported, disadvantages arise from gyroscopic reactions of the wheels which set up forces in opposition to those given to the steering mechanism by the hand of the driver and which cause the well known "shimmying" 30 movement of the front wheels. These disadvantages have been remedied by mounting the front wheels for independent movement and in such manner that they are constrained to move in planes parallel to the central longitudinal plane of the vehicle. One such arrangement, not new in itself, is herein shown diagrammatically in Fig. 1 wherein the front wheels are guided for rectilinear movement by the spring cylinder and piston suspension 3. I have just described this 35 mounting as one in which the wheels are guided for movement in planes parallel to the central longitudinal plane of the body, believing that this language when read in connection with the showing of Fig. 1 most quickly conveys the idea involved. Analysis, however, will show that the expression is inexact. Since the front wheels are turned in the steering movement, it is the usual substantially vertically steering pivot (not 40 illustrated) which moves in a plane parallel to the central plane and here again the language may be slightly inaccurate on account of possible camber of the pivot, but the motion in question will be well understood by those skilled in the 45 art aside from such niceties of expression. Fur-

thermore, on account of the fact that the wheels remain always equidistant from the central longitudinal plane of the vehicle, the advantage arises that the wheels do not alter the width of the track thereby causing an easy steering of 5

In an attempt to obtain the advantages with respect to steering arising from such a mounting of the front wheels and also to obtain the advantages arising when the vehicle is passing over a rough road from independently spring-supported wheels, vehicles have been constructed in which both rear wheels and front wheels have been mounted in the manner described. Vehicles thus constructed, however, do not hold the 10 road well and the comfort of the occupants is diminished because of a tendency which they show to accentuated rolling movement and to a large lateral inclination as compared with ordinary motor cars. The scientific experiments 15 made by me have demonstrated that there was a serious error of conception in constructing cars in this manner and in accordance with my present invention I have therefore provided for independent mounting of the rear wheels in a quite 20 different manner.

The subject may be understood from the following analysis. Referring to Fig. 1, if we imagine the vehicle shown as turning a corner, the body of the car under the influence of centrifugal 25 force will lean over towards the outside of the curve and take an inclined position, as shown in Fig. 2. The wheels 1, however, because of their method of mounting remain in planes equidistant from the central plane of the body. Consequently, when the body inclines, the front wheels 1 take a similarly inclined position. The resistance of the road acts at the ground-engaging portions 30 of the tires and the wheels tilt laterally about these points as pivots located on the surface of 40 the road. The body of the car follows the movement of the wheels and pivots about a point J also located on the road surface.

Now, if the rear wheels are similarly arranged, the axis of motion of the car body as a whole is 45 located at the road surface relatively remote from the center of gravity and the center of gravity acts through a relatively long lever arm tending to upset the body, or, considering another aspect, the center of gravity being relatively remote from 50 the center of oscillation, the amplitude of the lateral oscillations or rollings and the angle of inclination of the car body is great.

In accordance with my invention I therefore 55 mount the rear wheels 2 so as to permit angular

swinging movement of their planes with respect to the central longitudinal plane of the body. Thus in Fig. 3 I have by way of example shown the rear wheels 2 as mounted on half axles 6 and driven through Cardan or universal joints at 7 and 9. I prefer to support the axles from the body by means of longitudinally disposed leaf springs 4.

It will be apparent that since the wheels 2 are independently mounted they may move to pass over obstacles without tilting the body, as shown in Fig. 6. Under conditions such as above described tending to tilt the body the action at the rear of the car is quite different from the action at the forward end as described in connection with Fig. 1. This action of the car is shown in Fig. 5. The body of the car can tip while the rear wheels maintain their vertical position. In the case of turning a corner the rear wheels 2 maintain their vertical position and the body in tipping swings about the axis J₁ the pivotal center of the spring-supported half axles. In so swinging the car compresses the spring towards which it tips and permits expansion of the other. As shown in Figs. 4-6 each half axle 6 is bent upwardly to the differential gear 7 on which the half axles pivot therefore the advantage arises that the center of lateral oscillation or inclination J₁ of the body is located extremely higher and thereby located higher than the rotation axes of the rear wheels 2, which may allow a vertical arrangement of the rear wheel under normal load.

The said two centers of movement J and J₁ define an axis about which the body as a whole swings, which is line J—J₁ in Fig. 2. If G is the center of gravity, the lever arm through which the mass of the car works, which determines the tendency of its leaning or even tipping over and the amplitude of its rolling oscillations, is the distance G—B in Fig. 2, whereas in the case of a car both ends of which are mounted as shown in Fig. 1 or by equivalent means this lever arm would be the distance from the center of gravity to the ground, the line G—B₁. A vehicle embodying my invention, therefore, is stable against overturning movement and steady as regards transverse oscillations and in these points compares favorably with vehicles of standard construction in which the wheels of each pair are not independently supported while gaining the cushioning advantages of individual wheel suspension and the steering advantages of constructions of the type illustrated in Fig. 1.

As seen from the location of the line J—J₁ in Fig. 2, if the height of the center of gravity above the road surface remains the same, the length of the lever arm G—B decreases as the center of gravity moves rearwardly. Consequently it is obvious that the further to the rear that the center of gravity lies, the more fully the advantages of the invention are realized, and while the scope of my invention in its broader aspects is not limited to the location of the center of gravity, I prefer to locate this center as much as possible towards the rear or at least rearwardly of the central transverse plane M—M.

I am aware that the invention may be embodied in other specific forms without departing from the spirit or essential attributes thereof, and I therefore desire the present embodiment to be considered in all respect as illustrative and not restrictive; reference being had to the ap-

pended claims rather than to the foregoing description to indicate the scope of the invention.

I claim:

1. A motor vehicle comprising an underframe having front and rear pairs of wheels, each wheel independently connected to the underframe and spring-supported for individual movement, the front wheels having substantially vertical pivots providing for steering movement and each being mounted to move up and down with successive positions of its pivot substantially parallel and substantially equidistant from the central longitudinal plane of the vehicle whereby to define a swinging center for the body at the ground and the rear wheels each being mounted to permit angular swinging movement of their planes relative to such central plane whereby to define an elevated swinging center for the body, the two centers defining an inclined axis of oscillation for the body as a whole.

2. A motor vehicle as defined in claim 1 wherein the mass thereof is distributed to define a rearwardly located center of gravity, that is, nearer the rear wheels than to the front wheels.

3. A motor vehicle comprising an underframe having front and rear pairs of wheels, each wheel independently connected to the underframe and spring-supported for individual movement, the front wheels having substantially vertical pivots providing for steering movement and each being mounted to move up and down with successive positions of its pivot substantially parallel and substantially equidistant from the central longitudinal plane of the vehicle whereby to define a swinging center for the body at the ground and the mounting for the rear wheels comprising half axles each carrying a wheel and mounted for swinging movement in planes transverse to the aforesaid central plane under control of the springs whereby to define an elevated swinging center for the body, the two centers defining an inclined axis of oscillation for the body as a whole.

4. A motor vehicle comprising an underframe having front and rear pairs of wheels, each wheel independently connected to the underframe and spring-supported for individual movement, the front wheels being provided with a steering device for steering each front wheel and each front wheel being mounted on the underframe in such a manner that when the steering device is not actuated the said front wheel as a whole moves up and down in such a manner that the direction of such movement is parallel and equidistant from the central longitudinal plane of the vehicle whereby to define a swinging center for lateral inclinations of the body at the ground and the rear wheels each being mounted to permit angular swinging movement of their planes relative to such central plane whereby to define an elevated swinging center for lateral inclinations of the body, the two centers defining an inclined axis of lateral inclination for the body as a whole ascending from front to rear.

5. A motor vehicle as defined in claim 4, wherein the mass thereof is distributed to define a rearwardly located center of gravity, that is, nearer the rear wheels than to the front wheels.

6. A motor vehicle comprising an underframe having front and rear pairs of wheels, each wheel independently connected to the underframe and spring-supported for individual movement, a supporting device for each front wheel comprising a

guiding member connected to the underframe, a wheel carrier provided with a second guiding member said second guiding member cooperating with the said first guiding member in such a manner that it is guided in a vertical direction parallel to the longitudinal central plane of the vehicle by the said first guiding member and permitting a steering movement of the wheel so as to define a swinging center for lateral inclinations of the body at the ground, and spring means for spring-supporting the wheel against the underframe and a supporting device for the rear wheels comprising half axles each carrying a wheel and mounted for swinging movement in a vertical plane transverse to the aforesaid longitudinal central plane and spring means for springing said half axles against the underframe so as to define an elevated swinging center for lateral inclinations of the body, the two centers defining an inclined axis of lateral inclination of the body as a whole ascending from front to rear.

7. A motor vehicle comprising an underframe having front and rear pairs of wheels, each wheel independently connected to the underframe and spring-supported for individual movement, the front wheels being provided with a steering device for steering each front wheel and each front wheel being mounted on the underframe in such a manner that when the steering device is not actuated the said front wheel as a whole moves up and down in such a manner that the direction of such movement being substantially parallel and equidistant from the central longitudinal plane of the vehicle defines a swinging center for lateral inclinations of the body at the ground and the rear wheels each being mounted to permit angular swinging movement of their planes relative to such central plane, whereby to define a swinging center for lateral inclinations of the body said center being located above the converging point of the axes of rotation of the rear wheels the said two centers defining an inclined axis of lateral inclination for the body as a whole ascending from front to rear.

8. A motor vehicle as defined in claim 7, wherein the mass thereof is distributed to define a rearwardly located center of gravity, that is, nearer the rear wheels than to the front wheels.

50 9. A motor vehicle as defined in claim 7, wherein, under normal load of the vehicle, the rotation axes of the rear wheels extend in a substantially

horizontal direction and the center for lateral inclinations of the body is located above these rotation axes of the wheels.

10. A motor vehicle comprising an underframe having front and rear pairs of wheels, each wheel being independently connected to the underframe and spring-supported for individual movement, a supporting device for each front wheel comprising a guiding member connected to the underframe, a wheel carrier provided with a second guiding member cooperating with the said first guiding member in such a manner that it is guided in a substantially vertical direction generally parallel to the longitudinal central plane of the vehicle by the said first guiding member and permitting a steering movement of the wheel so as to define a swinging center for lateral inclinations of the body at the ground, and spring means for spring-supporting the wheel against the underframe and a supporting device for the rear wheels comprising half axles each carrying a wheel and mounted for swinging movement in planes transverse to the aforesaid longitudinal central plane and spring means for springing said half axles against the underframe, so as to define an elevated swinging center for lateral inclinations of the body, the two centers defining an inclined axis of lateral inclination of the body as a whole ascending from front to rear.

30 11. A motor vehicle comprising a body, an underframe therefor, a pair of front wheels and a pair of rear wheels, spring tensioned means for connecting each of said front wheels to said underframe, said means being so constructed and arranged that transverse swinging of the front part of said body and frame is about a center substantially at the ground, and spring tensioned means for connecting each of said rear wheels to said underframe, said second mentioned means 35 being so constructed and arranged that transverse swinging of the rear portion of the body and frame is about a center located above the converging point of the axes of rotation of said rear wheels, the said two centers defining an inclined axis of lateral inclination for the body as a whole ascending from front to rear.

12. A motor vehicle as defined in claim 11 wherein the mass thereof is distributed to define a rearwardly located center of gravity, that is, 40 nearer the rear wheels than to the front wheels.

RENÉ JEAN DEVILLERS.
